COMBINATION BEVERAGE COOLER AND
DISPENSER OR SIMILAR ARTICLEHarry C. Fischer, Columbus, and Louis P. Benua,
Gahanna, Ohio

Application April 10, 1952, Serial No. 19,278

Term of patent 14 years

(Cl. D2—3)

To all whom it may concern:

Be it known that we, Harry C. Fischer and Louis P. Benua, citizens of the United States, residing at Columbus and Gahanna, in the county of Franklin and State of Ohio, respectively, have invented a new, original, and ornamental Design for a Combination Beverage Cooler and Dispenser or Similar Article, of which the following is a specification, reference being had to the accompanying drawing, forming a part thereof.

Fig. 1 is a perspective view of a combination beverage cooler and dispenser or similar article, showing our new design;

Fig. 2 is a side elevational view; and

Fig. 3 is a rear elevational view.

The side of the combination beverage cooler and dispenser now shown in the drawing is identical in appearance to the side shown in Fig. 2.

We claim:

The ornamental design for a combination beverage cooler and dispenser or similar article, substantially as shown and described.

HARRY C. FISCHER.
LOUIS P. BENUA.
